(57) CLAIM

We claim the ornamental design for the seat cover with sports theme design, as shown and described.

DESCRIPTION

FIG. 1 is a front view of the seat cover with sports theme design.

FIG. 2 is a rear view of the claimed design.

FIG. 3 is a side view of the claimed design.

FIG. 4 is a top view of the claimed design.

FIG. 5 is a bottom view of the claimed design; and,

FIG. 6 is an isometric view of the claimed design.

The words “TEAM NAME” and/or “00” are depicted in FIGS. 1, 2, 3, and 6, and shall be construed as environmental matter that forms no part of the claimed design.

1 Claim, 6 Drawing Sheets

FIG. 1

FIG. 2

FIG. 3

FIG. 4

FIG. 5

FIG. 6
